CLAIM

The ornamental design for a brick, as shown and described.

DESCRIPTION

FIG. 1 is a front, left perspective view of the brick showing my new design;

FIG. 2 is a front, right perspective view thereof;

FIG. 3 is a left side view thereof, the right side view being a mirror image thereof;

FIG. 4 is a front view thereof, the rear view being a mirror image thereof;

FIG. 5 is a top plan view thereof; and,

FIG. 6 is a bottom plan view thereof.

The broken lines shown in FIGS. 1, 2, 5 and 6 depict unclaimed portions of the brick that form no part of the claimed design.
